CARBURETOR

Fritz Jeck, Basel, Switzerland

Application April 24, 1940, Serial No. 331,470
In Switzerland February 7, 1940

2 Claims. (Cl. 261—49)

The present invention relates to a carburetor which can be used for light and heavy fuel, in which two throttle valves are respectively provided in the two limbs of a substantially U-shaped passage for the air-fuel mixture, a needle-controlled fuel nozzle operated by a slideable control member, opening into one of the limbs of the passage between the said valves. The essence of the invention lies in the features that the U-shaped passage is arranged in a horizontal plane so that its two limbs (inlet passage and outlet passage) lie side by side and that the axes of the two throttle valves are transverse to one another and are coupled by a common linkage to the said control member in such a way that when the latter is moved in a direction to open or close the needle controlled nozzle the two throttle valves are simultaneously actuated in the same sense.

An example of embodiment of the invention is illustrated in the accompanying drawings—

Figure 1 shows the complete carburetor in vertical section on the line I—I of Figure 2;

Figure 2 is a horizontal section on the line II—II of Figure 1;

Figure 3 is a side elevation of the carburetor and

Figures 4 and 5 show details on an enlarged scale.

The carburetor shown in Figures 1-3 comprises a body 1 containing a substantially U-shaped through-passage for the air-fuel mixture, arranged in a horizontal plane. In this way the two limb passages lie side by side of which one will be hereinafter referred to as the inlet passage 1^a and the other as the outlet passage 2. On the mouth of the inlet passage 1^a is set an air strainer 3 and immediately succeeding this an air intake valve 4 having a horizontal axis is provided in the inlet passage. In the outlet 2 is provided a mixture throttle valve 5 having a vertical axis. These two valves 4 and 5, the axes of which are thus perpendicular to one another, are coupled together by a common linkage and are actuated simultaneously in the same sense. This linkage includes two lever arms 6 and 6^a releasably secured on the spindles of the respective valves 4 and 5, whereby a relative adjustment of the valves can be effected so that for example when one valve is completely closed the other is not yet quite closed. A needle-controlled fuel nozzle 8 communicating with the float chamber 7, opens from below into the inlet passage 1^a and its control needle 9 projects upwardly out of the inlet passage and is there un-

der the action of a helical spring 10 which urges it upwards off its seat on the mouth of the nozzle.

On the body 1 is an angle form guide block 11 for a slideable wedge 12 serving to control the needle 9, which block carries two upwardly directed bolts 13 the heads of which engage in a T-slot in the wedge. By turning the bolts 13 and locking them by the nuts 14, the position of the wedge can be vertically adjusted. As can be seen from Figure 3, the wedge 12 comprises a horizontal control surface 12^a and a sloping control surface 12^b. In one end position of the wedge 12 corresponding with the closed position of the nozzle a spring pressed knob 15 carried in the wedge presses on the needle 9 and holds the latter on its seat against the action of the spring 10. To the wedge 12 is coupled a pull-rod 16 to which the linkage 6 of the two throttle valves 4 and 5 is coupled through a compression spring 16^a carried in a tubular housing. The other end of the pull rod 16 is connected to a foot pedal or the like not shown. When the rod 16 is pulled by the foot pedal, the sliding of the wedge 12 in the same direction first moves knob 15 out of action so that the needle 9 rises until it abuts the horizontal control surface 12^a of the wedge 12. Upon further movement of the wedge 12, owing to the horizontal surface 12^a the needle at first remains in the same position whereas the two valves progressively open, until sloping surface 12^b reaches the needle and thereafter the needle 9 gradually rises and the two valves 4 and 5 continue to open until their full open position is reached. Owing to the interposition of the compression spring 16^a it is possible for the wedge 12 to continue moving after the two valves 4 and 5 have reached their full open position where they are checked by a stop 25 (Fig. 2), the spring 16^a then closing up.

As Figures 4 and 5 show, the needle controlled nozzle 8 is provided with a conical plug 17 having a central bore into which open four horizontal passages of different cross sections, set at 90° to one another. This plug is provided below with a hand knob 18 having a waved abutment face. The plug 17 is held in its working position in a screw sleeve 24 constructed as a plug seating, by means of a spring 19. By rotating the plug 17 by means of the knob 18 the nozzle can be set for a fuel flow corresponding to any one of the four passages in the plug. Beyond the nozzle 8 an exchangeable idling nozzle 20 is provided which when the carburetor is assembled projects into a bore located between the two passages 1^a and 2

and communicating with passage 2 (see Figures 1 and 2).

It can further be seen from Figure 4 that the needle 9 has a cylindrical portion 9^a cooperating with the bore of the nozzle 8 to give a minimum passage for fuel. In order to obtain satisfactory working of the carburetor when operating with heavy fuel (raw oil), it must be so adjusted that the complete withdrawal of the cylindrical part 9^a from the nozzle passage only takes place when the beginning of the sloping surface 12^b of the wedge 12 comes into engagement with the upper end of the needle 9.

In the space between the passage 1^a and the passage 2, as shown in Figure 2, an electric heating coil 21 is arranged the purpose of which is to pre-heat the fuel-air mixture before it reaches the engine. 22 is a spraying nozzle through which if desired water vapour can be admixed with the fuel-air mixture, and 23 is an adjustable nozzle for additional air.

The described carburetor is particularly suitable for motor vehicle and can be operated not only with gasoline but also with raw oil.

What I claim is:

1. In a carburetor the combination of a body, a U-shaped through passage therein set in a horizontal plane with its limb passages lying side by side, two valves arranged respectively in said

limb passages, with their axes perpendicular to one another, a fuel nozzle projecting into one of said passages between said valves, a needle slideable within said nozzle, having a cylindrical portion which in cooperation with the nozzle bore constitutes the minimum outlet area and a tapered portion, a slideable wedge controlling the movement of said needle in said nozzle, said wedge including an operative surface parallel with its sliding direction and a sloping operative surface succeeding said first named surface, said needle and surfaces being so related that said cylindrical portion is completely withdrawn from said nozzle when the beginning of said sloping surface comes into action, and means interconnecting said slideable wedge and said valves whereby said valves are opened and closed simultaneously with the opening and closing of the nozzle by the needle.

2. A carburetor as set forth in claim 1 also including stop means for checking the movement of said valves when they reach full open position, and yielding means in said interconnecting means whereby the sliding of said wedge can be continued after said valves reach full open position, said wedge being directly actuated and continued movement thereof further opens the fuel nozzle to enrich the mixture at full throttle.

FRITZ JECK.
